VALANCE FOR SUPPORTING DRAPERY RODS AND CURTAIN RODS

Filed April 29, 1940

UNITED STATES PATENT OFFICE

2,232,572

VALANCE FOR SUPPORTING DRAPERY RODS
AND CURTAIN RODS

Frank Strigler, New York, N. Y.

Application April 29, 1940, Serial No. 332,318

6 Claims. (Cl. 156—13)

This invention relates to valance for supporting drapery rod and curtain rod.

An object of this invention is to provide a highly improved valance of the character described, made of sheet metal and provided with steel butted tubing at its upper and lower edges to strengthen the valance, and also to serve as an ornamental trimming.

A further object of this invention is to provide an extensible valance of the character described, comprising two parts interconnected by a central portion slidably engaging the inner ends of the two parts of the valance, the butted steel tubing at the upper and lower edges of the two parts slidably engaging guides at the upper and lower edges of the center piece.

A still further object of this invention is to provide a strong, rugged and durable valance of the character described, which shall be relatively inexpensive to manufacture, attractive in appearance, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a top plan view of a valance embodying the invention, with parts broken away and in cross-section;

Fig. 2 is a cross-sectional view taken on line 2—2 of Fig. 1;

Fig. 3 is an end view of the improved valance;

Fig. 4 is a cross-sectional view taken on line 4—4 of Fig. 2; and

Fig. 5 is a cross-sectional view taken on line 5—5 of Fig. 2.

Referring now in detail to the drawing, 10 designates a valance embodying the invention, here shown as attached to a wall 11. The valance 10 comprises a pair of similar, symmetrically disposed parts 12 interconnected by a central member 14. The parts 12 and 14 of the valance 10 are made of sheet metal.

Each part 12 comprises a member 15 made of sheet metal and having a front wall 16, a wall 17 extending rearwardly at right angles therefrom, a wall 18 parallel to wall 16 and of narrow width, and a forwardly extending wall 19 sub-

stantially parallel to the wall 17, and formed with a flange 20 at its forward end extending from the wall 17. Wall 18 is formed with a key slot 22, for the purpose hereinafter appearing.

Wall 19 is formed with a pair of notches 24 and 25 in its upper edge to receive a drapery and curtain rod 28 and 29. The notch 25 is located adjacent flange 20, as shown in Fig. 4 of the drawing. The upper edge 27 of wall 19 is disposed below the upper edge of wall 17. In other words, walls 16, 17 and 18 are of equal height, but wall 19 and flange 20 are cut down in height so that the drapery and curtain rods 28 and 29 will be disposed below the upper edges of the valance.

The upper and lower edges of walls 16 and 17 are received within longitudinal slots of butted steel tubing 30 and 31. The tubing 30 and 31 are formed with longitudinal slots to receive the upper and lower edges of said walls 16 and 17, and the tubing is bent, as at 30a, with the walls 16 and 17 at the corners. The walls 16 and 17 may be attached to the steel tubing by brazing, welding or in any other suitable manner.

The interconnecting member 14 has inwardly curved guide portions 14a at its upper and lower edges to slidably receive the inner portions of the tubing 30 and 31. At the outer ends of wall 14 are rearwardly curved portions 14b adapted to contact the walls 16.

The valance may be hung on the wall 15 by engaging screws 11a fixed to the wall within the key openings 22.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A valance comprising a pair of similar, symmetrically disposed parts, each comprising a member having a front wall, a wall extending rearwardly from one end of said front wall, a wall extending from the rear end of the second wall and disposed parallel to the front wall, and a wall extending forwardly from said rear wall and formed in its upper edge with a pair of notches,

and a member interconnecting the inner ends of the front walls of said members.

2. A valance comprising a pair of similar, symmetrically disposed parts, each comprising a member having a front wall, a wall extending rearwardly from one end of said front wall, a wall extending from the rear end of the second wall and disposed parallel to the front wall, a wall extending forwardly from said rear wall and formed in its upper edge with a pair of notches disposed below the upper edges of said member, a member interconnecting the inner ends of the front walls of said members, and steel tubing on the upper and lower edges of the front and end walls of said members.

3. A valance comprising a pair of similar, symmetrically disposed parts, each comprising a member having a front wall, a wall extending rearwardly from one end of said front wall, a wall extending from the rear end of the second wall and disposed parallel to the front wall, a wall extending forwardly from said rear wall and formed in its upper edge with a pair of notches, a member interconnecting the inner ends of the front walls of said members and slidably mounted thereon, and steel tubing on the upper and lower edges of the front and end walls of said members, said rear walls each being formed with a key opening to receive means for hanging the valance on a wall.

4. A valance comprising a pair of similar, symmetrically disposed parts, each comprising a member having a front wall, an end wall extending rearwardly at right angles to the front wall, a rear wall extending from the rear end of said end wall and parallel to the front wall, and a wall extending inwardly from the rear wall and formed with a flange extending toward said end wall, and formed with a pair of notches in its upper edge, longitudinally slotted tubing receiving the upper and lower edges of the front and end walls of each member, and a central member having inwardly curved guide portions at its upper and lower edges

to receive the inner ends of the tubing on the front walls of said members.

5. A valance comprising a pair of similar, symmetrically disposed parts, each comprising a member having a front wall, an end wall extending rearwardly at right angles to the front wall, a rear wall extending from the rear end of said end wall and parallel to the front wall, and a wall extending inwardly from the rear wall and formed with a flange extending toward said end wall, and formed with a pair of notches in its upper edge disposed below the upper edge of said member, longitudinally slotted tubing receiving the upper and lower edges of the front and end walls of each member, and a central member having inwardly curved guide portions at its upper and lower edges to slidably receive the inner ends of the tubing on the front walls of said members, each rear wall being formed with a key slot to receive means for hanging the valance on a wall.

6. A valance comprising a pair of similar, symmetrically disposed parts, each comprising a member having a front wall, an end wall extending rearwardly at right angles to the front wall, a rear wall extending from the rear end of said end wall and parallel to the front wall, and a wall extending inwardly from the rear wall and formed with a flange extending toward said end wall, and formed with a pair of notches in its upper edge, longitudinally slotted tubing receiving the upper and lower edges of the front and end walls of each member, and a central member having inwardly curved guide portions at its upper and lower edges to receive the inner ends of the tubing on the front walls of said members, each rear wall being formed with a key slot to receive means for hanging the valance on a wall, the walls formed with a pair of notches being of less height than the front and end walls of said members.

FRANK STRIGLER.
